UNITED STATES PATENT OFFICE.

THOMAS ASHWORTH, OF URMSTON, ENGLAND.

FORMATION OF COPS IN SPINNING AND DOUBLING MACHINERY.

SPECIFICATION forming part of Letters Patent No. 674,723, dated May 21, 1901.

Application filed February 23, 1901. Serial No. 48,428. (No model.)

To all whom it may concern:

Be it known that I, THOMAS ASHWORTH, machinist, a subject of the King of Great Britain, residing at Lynwood, Urmston, in the county of Lancaster, England, have invented certain new and useful Improvements in the Formation of Cops in Spinning and Doubling Machinery, of which the following is a specification.

10 In the specification of a former patent, No. 613,106, dated October 25, 1898, spinning and doubling mechanism is described by which the spun fibrous yarn is wound into cops, the cops being wound nose downward, either upon 15 a bare spindle or on a thin tube placed upon such spindle. When winding the cops nose downward in this way, it is desirable that the part of the spindle on which the cop is wound should be made to taper slightly toward the 20 top, so that the cop when completed may readily be "doffed" or slipped off endwise from the spindle. Consequently the cops which are formed have a tapering hole extending through them, the larger diameter of which is 25 at their nose end. This has interfered with the cops being used for weft, as it was difficult to pass the tongue of the shuttle up through the narrow end of the hole at the base of the cop, it being necessary to place the cop 30 onto the tongue in this way as the yarn has to be drawn off from the nose end.

The object of this invention is to remedy this defect and to make the hole to taper in the right direction at the base end of the cop.

35 For this purpose I place onto the tapering point of the spindle a tube of paper or other suitable light material, which gradually increases in thickness from its lower to its upper end, so that its exterior forms an inverted 40 cone and is brought to a fine edge at its lower end. Longitudinal slits are made in the tube extending upward for some distance from its lower or thin end to give it a certain amount of elasticity and enable it to grip the spindle 45 with which it revolves while the cop is being wound upon it. In some cases also I place a thin tube of paper or other suitable light material around the exterior of the above tube, such thin tube being preferably coned both 50 externally and internally to correspond with the exterior of the tube around which it is placed. As the cop is wound base upward

the central hole which extends through it will at the base end of the cop conform to the coned surface of the tube which surrounds 55 the upper end of the spindle, so that this portion of the hole then tapers in the right direction to allow of a tongue or skewer being passed into it from the base end. When the cop is doffed, the split conical tube can readily 60 be withdrawn from it. The tube or tubes may be of any desired length. Usually it is desirable to make it somewhat less than half the length of the cop. The thin paper tube, if one has been used, may be allowed to re- 65 main within the cop.

My invention is illustrated in the drawings annexed.

Figure 1 is a vertical section of a tapering spindle passing up through a tubular inverted 70 flier and of a cop formed around the spindle. Fig. 2 is a similar section of the spindle with the paper or other tubes upon its upper end. Figs. 3 and 4 are exterior views of the two tubes. Fig. 5 is a vertical section of a cop 75 after it has been doffed from the spindle.

In Fig. 1, *a* is the inverted tubular flier, driven continuously by a band passing around the wheel *b*. *c* is a tapering spindle which passes up through the tubular flier and which, 80 as heretofore, has a constant rising-and-falling movement given to it in addition to a slow continuous upward movement and is revolved by the drag of the thread. *d* is a cop wound on the spindle nose downward. With a cop 85 so formed the diameter of the hole which extends through it is smaller at the base to the nose end.

In Fig. 2, *e* is a tube of paper or other suitable light material placed onto the upper end 90 of the spindle, this tube being in the form of an inverted cone, thin at its lower end and thick at its upper end. *f* is one of two longitudinal slits which are formed on opposite sides of the tube *e* to allow its lower end to 95 be somewhat expanded when it is placed onto the spindle. *g* is a conical tube of uniform thickness placed around the exterior of the tube *e*. When a cop is wound onto a spindle so surrounded by the tubes *e* and *g*, a cop *h* 100 is produced. When the cop is doffed, the tubes *e* and *g* come away with it, and the tube *e* can then readily be taken hold of by its projecting end and

withdrawn, while the tube *g* may be allowed to remain within the cop, as shown in Fig. 5.

The tube *e* might be used without the tube *g*; but it is in all cases preferable to use both 5 tubes.

It will be seen that when the cop is completed the longitudinal hole which extends through it tapers inward from both ends toward the center, as the tubes *e* and *g* are in 10 length somewhat less than half the length of the cop.

It is not necessary that the taper of the lower portion of the spindle upon which the nose or lower half of the cop is formed should 15 be the same as the taper of the upper portion of the spindle. The taper of the lower part may, in fact, be very slight or nearly cylindrical.

What I claim is—

1. In spinning and doubling mechanism the 20 combination of an inverted tubular flier driven continuously, a spindle passing up through it and tapering upwardly and an inverted conical tube placed upon the upper end of the spindle passing part way down it 25 and arranged in position for the base end of a cop to be wound around it.

2. The combination of the inverted tubular flier, *a*, tapering spindle, *c*, and tubes, *e* and *g*, surrounding the upper smaller end of the 30 spindle, substantially as described.

THOMAS ASHWORTH.
